UNITED STATES PATENT OFFICE

97,586

DESIGN FOR A STREET-TRAFFIC TIMING SIGNAL

James Henry Brady and John J. Roberts,
Louisville, Ky.

Application August 23, 1934, Serial No. 53,032

Term of patent 14 years

To all whom it may concern:

Be it known that we, James Henry Brady and John J. Roberts, both citizens of the United States and residents of Louisville, in the county of Jefferson and the State of Kentucky, have jointly invented a new, original, and ornamental Design for a Street Traffic Timing Signal, of which the following is a specification, reference being had to the accompanying drawing, which forms a part thereof.

On said drawing, the figure is an elevation in top perspective of our street-traffic timing signal.

The top and bottom plates between which are carried the anchoring means for the outer ends of the neon tubes, are of substantially the same contour.

We claim:—

The ornamental design for a street-traffic timing signal, substantially as shown and described.

In testimony whereof we have hereunto set our signatures.

JAMES HENRY BRADY.
JOHN J. ROBERTS.
